UNITED STATES PATENT OFFICE

CLARENCE C. KORNS, OF JOHNSTOWN, PENNSYLVANIA

SWITCH-THROWING MECHANISM

Application filed May 4, 1927. Serial No. 188,664.

One object of my invention is to provide a toggle mechanism for throwing railway switches and the like, of simplified construction.

5 Another object of my invention is to provide a switch-throw mechanism that may be easily assembled.

The present invention is an improvement in the structure, such for example as shown 10 in my Patent No. 1,313,995, issued August 26, 1919.

In the accompanying drawings

Figure 1 is a plan view of a portion of a railway track and my switch throwing device, with the cover removed;

Figure 2 is a view, partially in elevation and partially in section, of the switch throwing device with the cover in place, taken along a section line corresponding to the section line 20 II—II of Fig. 1; and

Figure 3 is a similar view taken along the section line III—III of Figure 1.

In the illustrated embodiment of the invention, I have shown a railroad track 2 comprising a main rail 3 and a switch point 4 controlled by a pull rod or tensioning member 5 connected to a switch-throw mechanism 6. This mechanism comprises a frame 7, a rocker arm 8 secured to the tensioning member 5, 30 and a biasing member 9 that cooperates with the rocker arm 8 for constituting a toggle mechanism. The frame is provided with a cover 7^a having an opening 7^b therein.

Referring to Figures 1 and 3, the switch 35 point 4 may be mounted in any suitable supporting structure 11 provided with an opening 12 for the reception of the pull rod 5 and a depending lug 13 secured to the switch point 4. The pull rod 5 is provided with a head 14 that engages one of the surfaces of the depending lug 13 for confining the latter between it and a sleeve 16 loosely mounted on the pull rod 5 in order that it may have longitudinal movement relative thereto.

45 Referring to Figures 1 and 2, the frame 7 is provided at one side with an opening 17 in which is seated a bearing mount 18 having a threaded opening 19 extending therethrough to the outer face of the frame 7. The opposite face of the mount 18 is provided with an

outwardly extending projection 21 having a groove 22 serving as a detent. A bearing pin 23 is adjustably threaded into the opening 19 and is provided at its inner end with a semi-spherical surface 24 for engaging a portion of the biasing member 9. The bearing 23 is provided with a transverse aperture 25 through which a pin 26 is adapted to extend for engaging the walls of the detent 22 whereby the bearing 23 is held in adjusted position since it is prevented from turning relatively to the bearing mount 18. The mount itself may co-operate with the flanges 27 disposed along the inner edge of the frame 7 for preventing relative rotational movement therebetween.

55 The biasing member 9 comprises a plunger 28 provided at one end with a socket 29 for the reception of the semi-spherical surface 24 of the bearing 23. The flange 31, constituting the wall of the recess 29, engages with one end of a coil spring 32. The other end of the plunger 28 is adapted to enter a socket 33 connected by a pin 34 to the rocker arm 8, and having a flange 35 forming a seat for the opposite end of the spring. Accordingly, the plunger 28 and the socket 33 are capable of relative movement with respect to each other under the influence of the spring 32 which tends to separate them.

70 The rocker arm 8 is constituted by an integral casting provided with intersecting openings at one end for the reception of the head 36 of the socket 33 and the pin 34. The other end of the rocker arm 8 is bifurcated to permit it to straddle the pull rod 5, and is provided with aligned openings 37 and 38 whose axis is normal to that of the pull rod 5. The upper opening 37 is of considerably greater diameter than the lower opening 38 whereby a connector 39 may be inserted therein from above the rocker arm, and is prevented from falling out of it by the smaller diameter of the opening 38. The connector 39 may extend through the opening 38 and be secured by a cotter pin or peening operation as desired. The rocker arm 8 is provided in its upper surface with an opening 41 cooperating with the opening 7^b for the reception of a suitable bar fulcrumed in the opening 7^b for throwing the mechanism. The bifurcated 75 80 85 90 95 100

ends of the rocker arm 8 are secured to the frame 7 by a pin 42 that extends through an inwardly projecting flange 43 on the frame 7 and into a recess 44 at the bottom of the frame 7.

5 The connector 39 is provided with an enlarged head 45 for cooperation with the opening 37 in the rocker arm 8, and with diametrically disposed flattened surfaces 46, one 10 of which is adapted to engage one end of the sleeve 16 and the other of which is adapted to engage a nut 47 disposed at the end of the pull rod 5. A centrally disposed opening 48 is provided in the connector for receiving the 15 pull rod and permitting movement relative thereto whereby a lost motion connection is constituted. The lower end of the connector 39 is materially reduced in diameter, as at 49, for engagement with the opening 38 in the 20 rocker arm 8.

In assembling the switch-throw apparatus the pull rod is attached to the switch point 4 and the sleeve 16 slipped into position thereon. The rocker arm 8 is secured by the pin 42 25 within the frame 7, and the biasing member 9 is assembled and connected to the rocker arm by the pin 34, after which the desired tension is placed on the spring by adjusting the position of the bearing 23. When the proper tension has been applied to the biasing 30 member 9, the pin 26 is inserted through the opening 25 of the bearing 23 and into the detent 22 to prevent further turning movement of the bearing. The connector 39 is 35 then dropped into the opening 38 in the rocker arm 8 and the pull rod 5 passed therethrough after which the nut 47 is placed upon the end of the latter. Since the switch-throw mechanism 6 is disposed in a horizontal position, it will be understood that the pins 26, 40 34 and 42, as well as the connector 39, may be inserted from above the open parts of the switch-throw mechanism 6, thereby materially simplifying the assembling of the device. 45

Assuming the parts to be in the position shown in Figure 1, and desiring to move the switch point 4, a suitable bar is fulcrumed in the opening 7^b and inserted in the opening 50 41. Force is applied to the bar to move the rocker arm to the left of the figure. Inward movement of the rocker arm serves to compress the spring 32 and to cause the connector 39 to move along the pull rod 5. At the 55 same time a relative turning movement occurs between the conical bearing surface 24 and the recess 29. When sufficient movement has been imparted to the rocker arm 8 to cause it and the tension device 9 to move past their center lines, the spring 32 expands to cause the connector 39 to strike the sleeve 16 a sharp blow by its flattened face 46, which movement causes positive movement of the switch point 4 to the desired position.

60 65 When it is desired to restore the switch

point 4 to its initial position, the rocker arm 8 is moved in a reverse direction whereupon the other face 46 of the connector 39 strikes the nut 47 a sharp blow to restore it to its initial position.

70 It will thus be seen that I have provided a switch-throw mechanism that is characterized by having a pull rod surrounded by a sleeve so that a sharp blow is delivered to the sleeve to move the associated switch point and that the component parts of the mechanism may be assembled while in a horizontal position by the insertion of a number of pins from above the device. Important details of my invention are found in the manner of assembling the toggle mechanism in the frame in order to adjust the same and to prevent the losing of the adjustment while the device is in operation. Further advantages arise from the provision of a one-piece rocker arm where- 75 by the parts thereof are prevented from moving out of the desired position during the repeated jars to which they are subjected both by reason of operation of the parts and by reason of traffic over the adjacent track. 80

85 Still further advantages arise from utilization of a tension member or pull rod of integral construction throughout its entire length whereby the provision of an adjusting connection therein is unnecessary. Where such adjusting connections have been provided it has been found that they not only tend to permit undesired relative movement, but also tend to develop looseness by reason of wear after they have been in use for a 90 95 comparatively short period of time.

It is to be understood that such changes in the number, arrangements, disposition and design of the component parts of my invention may be made without departing from the 100 105 scope of the appended claims.

I claim:

1. In a spring toggle mechanism, a frame comprising a guide, a toggle element, supporting means for the toggle element cooperating with said guide and having a detent therein, and a pin cooperating with said detent and a portion of said supporting means for preventing relative movement therebetween.

110 115 120 125 130 135 2. In a spring toggle mechanism, a frame comprising a guide, a toggle element, adjustable supporting means for the toggle element comprising a rotatable member, a bearing for the rotatable member cooperating with said guide and having a detent formed therein, and a pin cooperating with said rotatable member and detent for preventing relative movement of said rotatable member.

3. In a spring toggle mechanism, means for controlling the compression of the toggle mechanism comprising a biased toggle element, an adjustable rest therefor, a positioning detent and a pin passing through the 130 135

rest member and cooperating with the detent for controlling the position of the rest.

4. In a spring toggle mechanism, means for controlling the compression of the toggle mechanism comprising a biased toggle element, a rest therefor, a positioning detent, and a pin passing through the rest member and cooperating with the detent for controlling the position of the rest.

10 5. In a mechanical movement, an adjustable bearing member, a support for the bearing member having a detent, and a pin extending through the bearing member and cooperating with the detent to prevent movement of the bearing member.

20 6. In a mechanical movement, two members having relative angular movement, the position of one of which is adjustable, a substantially stationary detent, and a pin passing through the adjustable member and cooperating with the detent to restrict relative angular movement between the members.

25 7. In a mechanical movement, a tension member, a sleeve loosely mounted thereon, a rocker arm having lost motion relative to the tension member and having means for imparting movement to the sleeve member.

30 8. In a horizontally disposed toggle mechanism, a tension member, a rocker arm having openings therein adapted to receive a connecting member, and a connecting member in said openings having an upper portion of a greater dimension than the lower portion for connecting the rocker arm and tension member.

35 9. A connector pin comprising a head portion, a body portion having oppositely disposed flattened faces through which an opening extends, and a lower portion having materially smaller dimensions than the head portion.

40 10. In a switch throwing mechanism the combination with a supporting member having upper and lower openings of different dimensions, of a connector member, the upper portion of which is of a greater dimension than the lower portion, whereby the connector may be inserted in the supporting member and be maintained therein by the influence of the force of gravity.

45 11. A switch throw mechanism comprising a pivotally mounted support having upper and lower openings of different dimensions, and a connector having an upper portion of a greater dimension than the lower portion, whereby the connector is inserted in the openings in the support and retained therein by the influence of the force of gravity, said support having an opening therein 50 for the reception of a pull rod engaging the connector.

In testimony whereof I have hereunto set my hand.

CLARENCE C. KORNS.
